UNITED STATES PATENT OFFICE

HENRY JANSSEN, OF WYOMISSING, PENNSYLVANIA, ASSIGNOR TO TEXTILE MACHINE WORKS, OF WYOMISSING, PENNSYLVANIA, A CORPORATION OF PENNSYLVANIA

DESIGN FOR A HIGHWAY SIGN

Application filed December 20, 1930. Serial No. 38,043. Term of patent 14 years.

To all whom it may concern:

Be it known that I, HENRY JANSSEN, a citizen of the United States, residing at Wyomissing, in the county of Berks and State of Pennsylvania, have invented a new, original, and ornamental Design for Highway Sign, of which the following is a specification, reference being had to the accompanying drawing, forming part thereof.

Fig. 1 is a top plan view of a highway sign, showing my new design.

Fig. 2 is a corresponding face view thereof.
Fig. 3 is an edge view thereof.

I claim:

The ornamental design for a highway sign, as shown.

In testimony whereof I affix my signature.
HENRY JANSSEN.
